(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front elevational view of a first embodiment of a display screen or portion thereof with graphical user interface.

FIG. 2 is a front elevational view of a second embodiment of a display screen or portion thereof with graphical user interface.

FIG. 3 is a front elevational view of a third embodiment of a display screen or portion thereof with graphical user interface.

FIG. 4 is a front elevational view of a fourth embodiment of a display screen or portion thereof with graphical user interface.

FIG. 5 is a front elevational view of a fifth embodiment of a display screen or portion thereof with graphical user interface.

FIG. 6 is a front elevational view of a sixth embodiment of a display screen or portion thereof with graphical user interface; and,

FIG. 7 is a front elevational view of a seventh embodiment of a display screen or portion thereof with graphical user interface.

The broken lines showing portions of the display screen and the graphical user interface are for environmental purposes only and form no part of the claimed design.

UNITED STATES PATENT AND TRADEMARK OFFICE
CERTIFICATE OF CORRECTION

PATENT NO. : D813,268 S
APPLICATION NO. : 29/513543
DATED : March 20, 2018
INVENTOR(S) : Esteban Cabrera, Jr. et al.

Page 1 of 1

It is certified that error appears in the above-identified patent and that said Letters Patent is hereby corrected as shown below:

On the Title Page

Item (54), Title at Line 1, Change “THEROF” to --THEREOF--.

Item (72), Inventors at Lines 8-9, Change “San Deigo, CA (US);” for Eli Reihman to
--San Diego, CA (US);--.

Signed and Sealed this
Seventeenth Day of July, 2018

Andrei Iancu
Director of the United States Patent and Trademark Office
